(57) CLAIM

We claim the ornamental design for a reclinable patio chair, as shown and described.

DESCRIPTION

FIG. 1 is a perspective view of a reclinable patio chair showing our new design;

FIG. 2 is a right side elevational view thereof; the left side elevational view, absent the handle, being a mirror image thereof;

FIG. 3 is a front elevational view thereof;

FIG. 4 is a top plan view thereof;

FIG. 5 is a rear elevational view thereof; and,

FIG. 6 is a bottom plan view thereof.
